FIGURE TOY

Leonard C. Leaystrom, New Haven, Conn.

Application April 16, 1931, Serial No. 530,665

Renewed March 3, 1933

5 Claims. (Cl. 46—40)

This invention relates to improvements in toys, and has for its primary object to provide a toy which may be made to simulate certain movements of a human being.

5 Another object of the invention is to provide a toy in the form of a human being, having certain mechanism therein which, when operated, will cause the figure to tension a bow held thereby and release an arrow which will be projected 10 forwardly by the string of the bow.

A still further object of the invention is to provide, in a toy of the above described character, a novel mechanism of simple construction by means of which the necessary movements of an 15 arm may be obtained in order to produce the result above described.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or 20 modifications mark no material departure from the salient features of the invention as expressed in the appended claims.

In the drawings:—

Figure 1 is a view in perspective of the toy 30 embodying the present invention.

Figure 2 is a vertical sectional view through the body portion of the figure and the base showing the arm operating mechanism thereof.

Figure 3 is a view in horizontal section of the 35 figure taken on the line 3—3 of Figure 2.

Figure 4 is a sectional view taken on the line 4—4 of Figure 2.

Figure 5 is a detailed horizontal section through the center portion of the arrow holding hand 40 of the figure showing the control means therefor.

Figure 6 is a sectional view taken on the line 6—6 of Figure 5.

Referring more particularly to the drawings, wherein like numerals of reference indicate corresponding parts throughout the several views, the figure of the present toy is indicated generally by the numeral 1, and is shown standing upon a base or platform 2. The body of the figure 1 is hollow and also one of the legs, 50 in the present case the left leg. The left arm 3 of the figure is positioned in raised partly extended position, the hand 4 being turned inwardly slightly and holding a bow 5, which is preferably formed of a good spring steel. The 55 forefinger of the left hand is spaced sufficiently

from the other fingers to provide a passage 6 through which the arrow 7 may pass when it is projected forwardly by the string 8 of the bow in the manner hereinafter to be described. The left arm 3 of the figure is, of course, rigid with 60 the body.

The right arm 9 is made in two sections, the upper arm 10 and the lower or forearm 11, with which the hand 12 is integrally formed. The upper end of the portion 10 of the right arm 65 is turned to extend substantially at right angles, as indicated at 13, and passes through the opening 14 in the shoulder of the figure. This angular extension 13 of the upper arm portion is pivotally secured in the shoulder opening 14 70 by the vertical pivot pin 15 and it carries, upon its inner end, the hook 16, the free end of which is directed upwardly as shown.

An elbow joint is formed between the forearm 11 and the upper arm 10 by means of a vertical pivot pin 17 which passes through the hollow end of the upper arm into which the reduced portion of the forearm extends.

The hand 12 of the right arm is, as previously stated, integral with the forearm and is of 80 solid construction except for the thumb, which is indicated by the numeral 18. This thumb is pivotally attached to the body of the hand, as at 19, and oscillates relative thereto in a substantially horizontal plane. A chamber formed 85 transversely in the hand 12 houses a spring 20, one end of which is secured to the hand adjacent the outer side thereof, as at 21, while the other end terminates in a straight portion 22 which passes through an aperture 23 in the 90 side of the hand adjacent the thumb to be secured to the thumb, as at 24. It will thus be seen that the spring 20 normally maintains the thumb tight against the body of the hand. It will also be seen that by oscillating the right 95 arm 9 upon the pivot 15 it will move in substantially the same plane as that in which the aperture 6 through the left hand is located.

Thus, with an arrow extended through the aperture 6 or between the forefinger and second 100 finger of the left hand, with the string and feathered end of the arrow inserted between the thumb of the right hand and the adjacent index finger thereof, upon swinging the right arm to draw the hand thereof rearwardly the arrow and string will also be drawn back and thus bend the steel bow to place it under tension. The abutting surfaces of the thumb 18 and adjacent finger have complementary recesses therein as shown in Figures 5 and 6 to receive the rear end of the arrow. 110

When the tension of the bent bow reaches the point where it will overcome the ability of the spring 20 to hold the arrow and string between the thumb and first finger of the right hand, then, 5 of course, the arrow and string will be released and the arrow will be projected forwardly through the left hand.

The actuation of the right arm of the figure is accomplished by means of the following mechanism. Within the hollow body of the figure 10 there is positioned a vertical shaft or rod 25 which passes downwardly through the left leg and through the top of the box or platform 2. A bearing for the rod, in the top of the box, is provided in the form of a disk 26 which is carried by the rod and which rotates in the aperture 27 in the box top. Beneath the bearing disk 26 the rod is twisted to form a screw 28, or it may be joined to a screw of suitable size and pitch, 20 as desired. The lower end of the rod or the screw portion 28 thereof is provided with a reduced end or bearing pin 29 which extends into the bearing socket or step 30 in the bottom of the box.

25 Oscillatably mounted at one end upon one wall of the box, as at 31, is a lever 32 which is provided with a longitudinal slot 33 through which the screw 28 passes. The other or free end of the lever 32 projects through a suitable opening in 30 the back of the box so that it may be conveniently grasped between the fingers and vertically oscillated.

At the upper end of the rod 25 there is attached a right angularly extending arm 34 which is provided with a longitudinally extending slot 35, through which projects the free upwardly directed portion of the hook 16 carried by the arm 9.

From the foregoing description it will be readily seen that with a screw 28 of the proper twist 40 to impart a counter-clockwise rotation to the shaft 25 the right arm 9 will be oscillated and drawn backwardly so as to retract the bow string 8 and the arrow 7 which is gripped by the right hand of the figure. As previously stated, when 45 the tension of the bow 5 becomes so great that the spring 20 can no longer hold the arrow and bow string in place, they will be released and the arrow will be projected forwardly through the left hand of the figure.

50 Having thus described my invention, what I claim is:

1. A toy of the character described, comprising a simulation of a human figure, a bow supported in upright position by one hand of the figure, the other hand of the figure being joined to a jointed arm, means connecting said jointed arm with the body of the figure whereby the arm may be moved in a substantially horizontal plane, a shaft disposed vertically in the figure, means at 55 the lower end of the shaft for effecting oscillation thereof, a loose connection between the upper end of the shaft and the jointed arm whereby movement of the arm is effected through oscillation of the shaft about its longitudinal axis, and means for effecting the releasable engagement of the hand of the jointed arm with the string of said bow and with an arrow positioned thereagainst.

2. In a figure toy of the character described, 60 including a body having arms and hands, a hand having a passage formed transversely therein, a straight thumb pivotally secured to the body of the hand to be swung into position against the adjacent finger to extend parallel therewith, a spring disposed in said passage and having one

end secured therein at a point remote from the thumb and having its other end joined to said thumb at a point adjacent the pivot therefor to normally retain the same firmly against the said adjacent finger, and means for supporting an elongated body between the thumb and the adjacent finger comprising parallel recesses formed in the abutting faces of the thumb and finger.

3. A toy of the character described comprising a body simulating a human figure having a rigid 80 forwardly extended arm, an arm formed in two pivotally connected portions constituting upper and forearm portions, said upper arm portion having the shoulder end thereof pivotally mounted in the shoulder portion of the body, said body having a chamber therein adjacent the said shoulder portion into which the last named end of the upper arm extends, a bar secured in the pivoted shoulder end of said forearm and having its other end turned upwardly in said chamber, a shaft disposed vertically for oscillation in the body, a longitudinally slotted arm secured at one end to the upper end of said shaft and having the upturned end of said first bar disposed in the slot thereof, a screw forming a longitudinal 85 continuation of the lower end of said shaft, lever means engaging said screw and adapted to rotate the same, a hand formed at the free end of said forearm portion, a bow carried by said rigid arm, and an arrow adapted to be releasably connected 90 to the string of said bow to said hand, said slotted arm being oscillated by said shaft in a horizontal plane to impart forward and rearward movement to said pivotally mounted arm.

4. A toy of the character described, comprising a body simulating a human figure having a rigid 95 forwardly extending arm, an arm formed in two pivotally connected portions constituting upper and forearm portions, said upper arm portion having the shoulder end thereof pivotally mounted in the shoulder portion of the body, an arm pivotally mounted at one end in the upper part 100 of the body to oscillate in a horizontal plane, a sliding pivotal connection between said last arm and the pivotally mounted end of said upper arm portion, means for oscillating said last arm on its pivotal support, a hand formed at the free end of said forearm portion, a bow carried by said rigid arm and having a string thereon, and an arrow adapted to be releasably connected with 105 the string of the bow to said hand, said last arm upon oscillation imparting movement to said pivotally mounted two portion arm.

5. A toy of the character described, comprising a body simulating a human figure having a rigid 110 forwardly extending arm, an arm formed in two pivotally connected portions constituting upper and forearm portions, said upper portion having the shoulder end thereof pivotally mounted in the shoulder portion of the body, an arm pivotally mounted at one end within the upper portion 115 of said body to oscillate in a horizontal plane, said last arm having a longitudinal slot therein, a member disposed vertically in the body and carried by the shoulder end of the upper arm portion and slidably engaged in said slot, means for effecting the oscillation of said last arm on its pivotal mounting, a hand formed at the free 120 end of said forearm portion, a bow carried by said rigid arm and including a string, and an arrow adapted to be releasably connected with the string of said bow to said hand, said last arm when oscillated imparting movement to said pivotally mounted arm.
